F. S. DENNEEN & J. R. BROWN.
FLUID PRESSURE VALVE,
APPLICATION FILED AUG. 27, 1910.

1,032,470.

Patented July 16, 1912.

UNITED STATES PATENT OFFICE.

FRANCIS S. DENNEEN AND JOHN ROWLAND BROWN, OF MANSFIELD, OHIO, ASSIGNEES
TO THE OHIO BRASS COMPANY, OF MANSFIELD, OHIO, A CORPORATION OF NEW
JERSEY.

FLUID-PRESSURE VALVE.

1,032,470.

Specification of Letters Patent. Patented July 16, 1912.

Application filed August 27, 1910. Serial No. 579,279.

To all whom it may concern:

Be it known that we, FRANCIS S. DENNEEN and JOHN R. BROWN, citizens of the United States, and both residing at Mansfield, in the county of Richland and State of Ohio, have invented certain new and useful Improvements in Fluid-Pressure Valves, of which the following is a specification.

This invention relates to fluid pressure valves, and has for its primary object to provide a valve of improved construction, combination and arrangement of parts which shall be durable and efficient in action, and by means of which the valve can be made susceptible to a light pressure on the valve stem without the loss of pressure fluid medium around the valve stem.

One of the objects of the present invention is to provide an improved construction, combination and arrangement of parts in valve operating mechanisms for devices of this nature.

Another object is to provide an improved valve operating lever and improved means for mounting the same.

Other and further objects will appear in the specification and be more specifically pointed out in the appended claims, reference being had to the accompanying drawings exemplifying the invention, and in which—

Figure 1 is a cross section of a sander valve constructed in accordance with the principles of this invention. Fig. 2 is a similar cross section of a whistle valve constructed in accordance with the principles of this invention. Fig. 3 is a top plan view of an engineer's valve with two valves constructed in accordance with the principles of this invention coöperatively arranged therewith.

Referring more specifically to the drawings, and first of all to the embodiment shown in Fig. 1, a valve body 1 of well known construction comprises an inlet opening 2 and an outlet opening 3, with a valve seat 4 operably related to which is a valve 5 on a valve stem 6, said valve stem being provided with an extension 7 below, reciprocably supported by a cap 8, which is threaded into an opening in the valve body or housing 1. Extending around the portion 7 of the valve stem is a spiral spring 9, which coöperates with the pressure of the fluid entering through the inlet 2, to hold

the valve 5 to its seat 4. In the upper wall of the valve body is provided a valve stem opening through which the valve stem 6 projects, said opening being sufficiently large to permit the valve stem to slide freely therethrough. Said body portion or housing 1 of the valve is provided above with a socket constituted by an annular threaded flange 10 surrounding the outer end of the valve stem 6. Seated within this socket is a flexible diaphragm 11 of any suitable material, said diaphragm being imperforate and fluid tight, and preferably resting at its center upon the upper end of the valve stem 6. In order to clamp said diaphragm 11 about its edges within the socket 10, a plug or diaphragm nut 12 provided with an enlargement 13 seats upon the diaphragm 11, the outer peripheral edge of the enlarged portion 13 being threaded to engage the threaded socket 10, thus providing a diaphragm-containing chamber with two compartments, one above and the other below said diaphragm. The plug 12 is provided with a central axial opening within which is reciprocably mounted a plunger or diaphragm stem 14 provided below with an enlargement or head 15, which preferably rests directly upon the diaphragm 11. The central aperture in the diaphragm nut 12 is made of sufficient size to permit the plunger or diaphragm stem 14 to reciprocate freely therein, neither the valve stem 6, nor the diaphragm stem 14 being packed. Said stems are therefore mounted in such a manner that they are easily reciprocated by a comparatively light pressure. Ordinarily, considerable leakage would occur around the valve stem, and in order to make it possible to use a construction of this kind without the attendant loss of fluid pressure, the diaphragm 11 is provided, which forms a fluid tight closure for the opening in the upper wall of the valve housing.

In order to provide means for reciprocating the plunger 14 for operating the valve stem 6, the operating lever 16 is pivotally mounted about a pin 17 supported between two parallel cheeks or lugs 18. The lugs 18 are preferably integral with a collar 19 rotatably mounted upon the upper cylindrical portion of the diaphragm nut 12, said collar being provided on one side with a protuberant portion 20 within which is threaded a grub or other screw 21. The grub 21 is

2
 provided with a pointed end to adapt it to engage a V-shaped groove 22 extending circumferentially around the upper portion of the plug 12. Said grub 21 may be tightened 5 and loosened to hold the collar fixed in any position to which it may be adjusted upon said plug 12. In order to make the operating lever 16 removable, it is provided at its pivoted end with a slot 23 extending to the 10 edge of said lever to permit it to be passed into and out of engagement with the pivot 17. From an inspection of Fig. 1, it will be seen that the plunger 14 projects above the upper surface of the plug 12. The lever 15 16 impinges upon the plunger 14, for which purpose it is provided with a flat portion 24, which flat portion, after the lever 16 has been depressed sufficiently to open the valve 5, rests upon a protuberance or lug 25 to 20 limit the downward movement of said lever. Said lug 25 preferably forms an integral portion of the collar 19. The lever 16 is provided on its outer swinging end with a finger hold 26, the valve 5 therefor being 25 operable anywhere within a radius equal to the length of the lever 16 from the axis of the valve stem 6.

Referring now to Fig. 2, which illustrates the application of the invention to a whistle 30 valve, all the parts are of exactly similar construction with the exception of the operating lever 27, which in this embodiment comprises a short lever pivoted at 28 adjacent one end and provided with an eye 29 35 at its outer swinging end for the attachment of a draw cord 30. Adjacent the inner end said lever is provided with an offset lug 31, which impinges directly upon the diaphragm plunger 14'.

40 It is oftentimes desirable to have devices of this nature for controlling the deposit of sand on the track, and the sounding of the whistle or alarm within easy reach of which-ever hand the engineer may employ to operate the engineer's valve. For this purpose two valves constructed similarly to that shown in Fig. 1 of the drawings may be connected to the same air supply, and by means of the rotatably adjustable handles 45 45 50 55 38 and 39, which may be set in any desired relation to the handle of the engineer's valve, be employed to operate either the sander or the whistle. This arrangement is shown diagrammatically in Fig. 3, in which the common air supply pipe is indicated at 32, being provided with a T 33. Connected in branch pipes 34, 35 are valves 36, 37, the operating levers 38, 39 of which may be revolved in the manner already described to 60 bring the finger holds 40, 41 adjacent to the operating lever 42 of the engineer's valve.

65 While the sander valve is usually placed within easy reach of the engineer's valve handle, it may, of course, be installed at any other convenient point in the car, the most

important features of this valve being the non-leaking easy valve action, and the adjustable arrangement of the handle with respect to the valve body. Heretofore, much trouble has been experienced with whistle 70 and sander valves because of the leakage around the valve stem when the valve is operating. If packing is used around this stem to prevent leakage, the valve spring which causes the valve to close must be 75 amply strong to overcome the resistance of the packing, so that this combination of circumstances would make the valve too hard to operate satisfactorily with thumb pressure. 80

What I claim is:

1. The combination of a valve housing provided with a valve chamber and a diaphragm containing chamber, a valve and valve stem movably mounted in said valve 85 chamber, the valve stem projecting into the diaphragm chamber, a diaphragm against which the valve stem presses, a nut to close the diaphragm chamber and to bind the diaphragm periphery against the valve 90 housing, said nut being formed with a projection, a plunger stem extending through the said nut and bearing against the diaphragm, a lever seated in said projection and adapted to bear against the said plunger 95 stem to open the valve.

2. The combination of a valve housing provided with a valve chamber and a diaphragm containing chamber, a valve and valve stem movably mounted in the said valve chamber, the valve stem projecting into the diaphragm chamber, a diaphragm pressing against the valve stem, a nut to close the diaphragm chamber and to bind the diaphragm against the valve housing, the nut being formed with a laterally grooved projecting portion, a plunger stem extending through the nut and bearing against the diaphragm, a collar mounted upon the projecting portion of the said nut, 100 means to secure the collar to said projecting portion, and a lever pivoted on the collar, the outer end of the plunger stem bearing against the lever and the lever being operable in conjunction therewith to open the 110 valve. 115

3. The combination of a valve housing provided with a valve chamber and a diaphragm containing chamber, a valve and valve stem movably mounted in said valve 120 chamber, the valve stem projecting into the diaphragm chamber, a diaphragm pressing against the valve stem, a nut to close the diaphragm chamber and to bind the diaphragm against the valve housing, the nut being formed with a laterally grooved projecting portion, a collar formed with projecting lugs and movable about the said 125 grooved portion, means to bind the collar to the said grooved member, a plunger stem 130

extending through the nut, one end bearing upon the diaphragm and the other end projecting from the nut and a lever pivoted in the said projecting lugs, the lever bearing 5 against the projecting end of the plunger stem to open the valve.

4. The combination of a valve housing provided with a valve chamber and a diaphragm containing chamber, a valve and 10 valve stem movably mounted in said valve chamber, the valve stem projecting into the diaphragm chamber, a diaphragm pressing against the valve stem, a nut to close the diaphragm chamber and to bind the diaphragm against the valve housing, an adjustable collar formed with projecting lugs on opposite sides and adjustably mounted on the said nut, a plunger stem extending through the nut, and a lever pivoted in the 15 projecting lugs at one side of the collar, adapted to engage the stem, and engaged by the projecting lug at the opposite side of the collar to stop the lever in the operation of opening the valve.
- 20 5. The combination of a valve housing provided with a valve chamber and a diaphragm containing chamber, a valve seat arranged longitudinally of the housing, a diaphragm and means to secure the same in the 25 diaphragm chamber, a cap member formed with a cylindrical opening, a valve stem one end of which is movably seated in said recess and the other end of which extends through the valve opening and the housing wall into the diaphragm chamber, a valve mounted on the stem to close the valve opening, means to open the valve, and a spring engaging the valve and the recessed cap to close the valve 30 opening.
- 25

other end extends through the housing to 35 engage the diaphragm, a valve on the valve stem to engage the valve seat and to stop the stem from distending the diaphragm, and resilient means to press the valve in engagement with the valve seat.

40 6. The combination of a valve housing provided with a valve chamber and a diaphragm containing chamber, a valve seat arranged longitudinally of the housing, a diaphragm and means to secure the same in the 45 diaphragm chamber, a removable cap member formed with an inner recess in alignment with the valve opening, a valve stem one end of which is movably seated in said recess and the other end of which extends through 50 the valve opening and the housing wall into the diaphragm chamber, a valve mounted on the stem to close the valve opening, means to open the valve, and a spring engaging the valve and the recessed cap to close the valve 55 opening.

In testimony whereof we have signed our names to this specification, in the presence of two subscribing witnesses, on this seventeenth day of August A. D. 1910.
